(57) **CLAIM**

The ornamental design for a personal robot, substantially as shown and described.

DESCRIPTION

FIG. 1 is a perspective view of the personal robot showing the new design.

FIG. 2 is a front elevation view thereof.

FIG. 3 is a rear elevation view thereof.

FIG. 4 is a side elevation view, the opposite side being a mirror image thereof.

FIG. 5 is a top view thereof.

FIG. 6 is a bottom view thereof.

FIG. 7 is a front elevation view of the personal robot in a collapsed position.

FIG. 8 is a perspective view of a second implementation of the personal robot showing the new design.

FIG. 9 is a front elevation view of the second implementation.

FIG. 10 is a rear elevation view of the second implementation.

FIG. 11 is a side elevation view of the second implementation, the opposite side being a mirror image thereof.

FIG. 12 is a top view of the second implementation.

FIG. 13 is a bottom view of the second implementation; and, FIG. 14 is a front elevation view of the second implementation of the personal robot in a collapsed position.

The broken lines in the Figures show portions of the personal robot that form no part of the claimed design.

1 Claim, 14 Drawing Sheets
